Letters received during the period indicated in the
a preceding letter will be forwarded to the appropriate
office responsible for action to protect your
property. This record can serve as evidence of damage and
will facilitate prompt handling of the problem. Your
insurance agent will be advised of the damage and necessary
steps will be taken to repair or replace the property. Your
agent will also be advised of the amount of insurance
available to cover the damage. Your agent will be advised
of the amount of insurance available to cover the damage.
UNITED STATES 2,6

UNITED STATES PATENT OFFICE

2,608,434

This invention relates to a motor coach body or the like, and more particularly to a body construction having panels with improved window wells formed therein.

It is a general object of the invention to provide a coach body, including one or more panels which form part of the side structure of the body, wherein such panel has an outwardly disposed planar portion which is secured to the frame and comprises part of the outer body skin, and wherein said panel has an inwardly dished portion comprising a window well.

Another object is to provide a coach body with a panel as described above and wherein the window well has a horizontal depth approximately equal to the horizontal thickness of the frame, whereby the inner side of the window well will form a portion of the inner skin of the coach body.

Another object is to provide a panel including an outer skin portion and a window well portion formed by dishing the panel, and wherein the outer skin portion has means for securing it to a panel located therebelow.

The above and other objects and advantages will more fully appear from the following description made in connection with the accompanying drawing, wherein:

Fig. 1 is a perspective view of a motor coach embodying the invention.

Fig. 2 is an enlarged section taken approximately on the line II-II of Fig. 1.

Fig. 3 is an enlarged fragmentary perspective view of one of the window well panels, showing other portions of the coach body in section.

Fig. 4 is an enlarged fragmentary section taken approximately on the line IV—IV of Fig. 3.

Referring to the drawing, the coach body 6 includes vertical frame members 8 and 10. The frame member 8 has a vertical web 12 with oppositely extending and angularly disposed flanges 14 and 16. The frame member 10 is preferably of angle iron and includes flanges 18 and 20 which lie at right angles to each other.

In Fig. 3 there is shown a sheet metal panel 22 which has an outwardly disposed vertical planar portion 24 and an inwardly dished planar portion 26. The vertical edges of the panel 22 are turned inwardly as at 28 and located between the vertical frame members 8 and 10. Nutted bolts 30 extend through the frame members and the panel edges 28 to tie them together as a rigid unit.

As shown in Figs. 2 and 3, the inwardly dished panel portion 26 is defined by side walls 32 and

The bottom edge of the panel 22 is crimped as at 56 to receive the upper edge of a molding strip 58 and said molding strip in turn has its lower edge 60 crimped to fit over the upper edge of a panel 62 which is disposed therebelow. Consequently it is seen that the drain outlet aperture 54 is located a considerable distance above the bottom of the coach body. This produces adequate drainage of the window well at a point where muddy water will not be splashed into the window well by the wheels of the coach or of adjacent vehicles.

The panel 22 provides a one-piece structure in which a window well is formed and the horizontally spaced planar portions 24 and 26 are conveniently utilized to provide portions of the outer and inner skins of the coach body. The panel or panels 22 are easily and rigidly held by the frame members 8 and 10 to produce a strong

coach body unit which can be readily assembled in successive sections depending upon the length of the body desired.

A panel with a window well formed in accordance with my invention insures a leak-proof structure and also reduces the cost of finishing the inside of the body since the window well panels 26 can form part of the inner skin or a support for a continuous inner skin portion such as the sheet 36.

It will be understood that changes can be made in the specific details of the structure without departing from the spirit of the invention.

I claim:

1. In a coach body, a body panel of sheet material, portions of which lie in inwardly and outwardly disposed vertical planes, that portion in the outwardly disposed plane comprising part of the outer skin of a coach body, the portion in the inwardly disposed plane comprising a part of the inner skin of a coach body, the outer portion being of greater over-all extent than the inner portion, connecting structure between the sides and bottom of the inner portion and adjacent parts of the outer portion, and said inner portion and connecting structure constituting a window well.

2. In a coach body, a frame having spaced uprights, a panel supported by the uprights, a portion of the panel lying at the outer sides of the uprights to provide an outer skin portion, and another portion of the panel being dished inwardly between the uprights to provide a window well the inwardly dished portion comprising a panel portion disposed above and in inwardly spaced parallel relation to the outer skin portion of the panel.

3. The structure in claim 2, and said dished portion having a considerable area thereof in an upright plane lying approximately flush with the inner sides of the uprights.

4. In a coach body, a frame having spaced uprights, a panel supported by said uprights, a lower portion of the panel lying at the outer sides of the uprights to provide an outer skin portion, an upper portion of the panel being dished inwardly to provide a window well, and a second panel secured to said frame at the outer side thereof to provide an outer skin portion, said second panel overlying said window well in outwardly spaced relation thereto, and the lower edge of said second panel being spaced from the bottom of said window well to permit water to drain outwardly from said window well and beneath the edge of said second panel.

5. In a coach body, a frame, a panel supported by said frame, a portion of said panel being disposed in a plane at the outer side of said frame to provide an outer skin portion, another portion of the panel being dished inwardly to provide a window well, and a second panel overlying said window well in outwardly spaced relation thereto, and a drain aperture at the bottom of said window well and leading to the outer side of the outer skin portion of said first-mentioned panel.
